US0D1060069S

(12) **United States Design Patent** (10) Patent No.: **US D1,060,069 S**
 (45) Date of Patent: ** Feb. 4, 2025

(54) **ALCOHOLMETER**(71) Applicant: **Dräger Safety AG & Co. KGaA**,
 Lübeck (DE)(72) Inventor: **Michael Richenberger**, Lübeck (DE)(73) Assignee: **Dräger Safety AG & Co. KGaA**,
 Lübeck (DE)(***) Term: **15 Years**(21) Appl. No.: **29/746,355**(22) Filed: **Aug. 13, 2020**(51) LOC (15) Cl. **10-04**

(52) U.S. Cl.

USPC .... **D10/81**(58) **Field of Classification Search**

USPC D10/70, 75, 51, 57, 98, 96, 81; D24/186,

D24/112, 114, 169, 216

CPC A61B 5/6801; A61B 5/082

See application file for complete search history.

(57)

CLAIM

The ornamental design for a alcoholmeter as shown and described.

DESCRIPTION

FIG. 1 is a perspective view of the new alcoholmeter design;

FIG. 2 is a front view thereof;

FIG. 3 is a rear view thereof;

FIG. 4 is left side view thereof;

FIG. 5 is a right side view thereof;

FIG. 6 is a top view thereof; and,

FIG. 7 is a bottom view thereof.

The broken lines depict portions of the article that form no part of the claimed design.
